BOBBIN AND METHOD OF MAKING SAME

Richard G. Turner, Worcester, Mass., assignor
to Crompton & Knowles Loom Works, Worcester, Mass., a corporation of Massachusetts

Application November 26, 1948, Serial No. 62,203

6 Claims. (Cl. 139—206)

1

This invention relates to improvements in bobbins to be used with electric weft detecting systems in looms and to the method of their manufacture, and it is the general object of the invention to provide a bobbin with a ferrule of generally conical form fitting steps on the bobbin in such manner as to hold the ferrule firmly to the bobbin.

In the past it has been customary to provide bobbins for electric weft detector systems with cylindrical ferrules for engagement with the two feeler fingers or electrodes of the weft detector. These ferrules have generally been cylindrical with a diameter about the same as that part of the bobbin on which the weft is wound. When the weft on such a bobbin is almost exhausted it wraps around the bobbin barrel several times and does not unwind freely. Breakage of the weft frequently results due primarily to the fact that the ferrule is cylindrical.

It is an important object of this invention to provide a bobbin with a conical metallic ferrule adjacent to the bobbin butt and firmly secured thereto in such manner that it will not slip off the bobbin. In order that the ferrule, which constitutes the detecting zone of the bobbin, may be held tightly to the bobbin it is provided with a series of steps which may have a taper opposite to the general taper of the detecting zone. More generally at least one of the steps is made so that a part of it at a given distance from the butt has a diameter less than the diameter of another part thereof more distant from the butt. The aforesaid steps therefore need not necessarily be conical, since the relation of the diameters of the steps already mentioned can be attained with steps having forms other than conical.

It is a further object of the invention to provide an improved method for making the bobbin as already described, the method including the steps of waterproofing the bobbin and then depositing the ferrule electrolytically.

With these and other objects in view which will appear as the description proceeds, the invention resides in the combination and arrangement of parts hereinafter described and set forth.

In the accompanying drawings, wherein a convenient embodiment of the invention is set forth, Fig. 1 is a plan view showing the improved bobbin with its ferrule in contact with a type of electric weft detector which is in common use on certain types of weft replenishing looms.

Fig. 2 is an enlarged transverse section of the bobbin on line 2—2, Fig. 1.

2

Fig. 3 shows the bobbin after the first step in the formation of the ferrule has been performed, Fig. 4 is an enlarged transverse section on line 4—4, Fig. 3,

Fig. 5 is a longitudinal section through the bobbin after the second step in the formation of the ferrule has been performed, and

Fig. 6 is an enlarged diagrammatic view showing the relation between the body of the bobbin, the enamel coating, the electric conducting paint, and the metal ferrule.

Referring particularly to Fig. 1, the weft detector designated at D has right and left detector fingers 10 and 11 which may be connected by wires 12 and 13 to a loom controlling circuit. The detector comprises a base or body 16 made of insulating material and in which the fingers 10 and 11 are slidably backwardly and forwardly. A detector may be secured to a support 14 by means of bolts 15.

The bobbin set forth herein will have some characteristics common to bobbins already in use, such for instance, as a butt 20 provided with the usual rings 21 by which the bobbin is held in the shuttle of a weft replenishing loom, and a barrel 22 on which weft is wound. The barrel 22 may terminate with the usual tip 23. The body 24 of the bobbin may be made of a cheap but absorbent material, such as wood or paper. At periodic intervals during loom operation the bobbin is presented to the detector D, and so long as sufficient weft for continued weaving is present on the bobbin the fingers 10 and 11 will be kept insulated from each other, but when the weft is depleted the fingers of the detector are electrically connected by a part of the bobbin to be described to close a loom controlling electric circuit.

The matter thus far described, except for that part of the bobbin which electrically connects the detector fingers 10 and 11, may be the same as that heretofore used.

The bobbin forming the subject matter of the present invention may have a part of its body 24 between the butt 20 and the barrel 22 formed with a general taper which diminishes in a direction from the butt toward the tip. This general taper is indicated at 25 in Fig. 5 and corresponds to the detecting zone 26 of the bobbin. The tapered part 25 is provided with a plurality of steps 27 which as shown in Fig. 5 are tapered toward the butt. There may be as many steps as are required to provide the detecting zone of the bobbin.

55 The bobbin is then dipped in an enamel and

baked to provide an inclosing coating which prevents entry of water or steam into the wood of the bobbin. This coating is indicated at 28 and preferably though not necessarily waterproofs the entire bobbin. The tapered part 25 is then covered with a layer of electric conducting paint 29 containing finely divided metallic particles, such as silver. This paint is applied to the exterior of the taper 25 and covers that part of the bobbin corresponding to the detecting zone.

The bobbin is then placed in an electrolytic bath and connected to one of the electrodes thereof so that a metallic ferrule F may be deposited directly on and be bonded to the coat of paint. During deposition of the ferrule the enamel coating 28 prevents the wood of the bobbin from absorbing the acid of the electrolytic bath. The paint conforms to the shape of the steps as will also the metal shell or ferrule, and it is for this reason that the ferrule will be held firmly to the bobbin and will not be able to slide thereon in a direction from the butt toward the tip. I have found that a slight amount of taper on the steps will be sufficient to hold the ferrule very firmly to the bobbin.

The steps will be separated from each other by radial shoulders 30, see Fig. 6, which will also be covered with the paint and deposited metal so that the ferrule will be a single piece of metal and be able to close a circuit through the detector fingers 10 and 11 wherever the latter engage it.

While the steps have been described as tapered toward the bobbin butt the invention is not necessarily limited to steps of this form. It will be sufficient if the steps are of such form that one diameter thereof is less than another diameter thereof more distant than the one diameter from the bobbin butt. Thus, in Fig. 5 the diameter *a* of one of the steps is less than diameter *b* of the same step but farther from the butt 20 than is diameter *a*.

From the foregoing it will be seen that the invention sets forth a bobbin having a weft detecting zone which tapers generally in a direction from the butt toward the tip thereof, thereby insuring better unwinding of the weft than is the case with cylindrical ferrules. The detecting zone is made up of a series of steps which may be tapered in a direction opposite to the general taper of the zone. Because of the reverse tapers of the steps the ferrule is very securely attached to the bobbin. It will also be seen that the invention sets forth a method of making a bobbin with a metallic ferrule including the steps of providing a non-conducting base, such as wood, with steps, waterproofing the bobbin, coating the steps with a layer of electric conducting paint or the like, and thereafter bonding a metallic ferrule to the layer of paint by electrolytic action.

Having thus described the invention it will be seen that changes and modifications of the foregoing specific disclosures may be made without departing from the spirit and scope of the invention.

What is claimed as new is:

1. In a bobbin for use with the electric weft detecting system of a loom, a bobbin body having a detecting zone tapering generally from the butt toward the tip of the bobbin, steps on said zone, a waterproofing coating on the bobbin, a layer of electric conducting paint on the coating on the

detecting zone, and a metallic ferrule bonded to the layer of paint.

2. In a bobbin for use with the electric weft detecting system of a loom, a bobbin body having a detecting zone tapering generally from the butt toward the tip of the bobbin, steps on said zone, at least one of said steps being of such form that one diameter thereof is less than another diameter thereof more distant than said one diameter from the bobbin butt, a waterproofing coating on said zone, a layer of electric current conducting paint on the coating on said zone, and a metallic ferrule bonded to said layer of paint.

3. In a bobbin for use with the electric weft detecting system of a loom, a bobbin body having a detecting zone tapering generally from the butt toward the tip of the bobbin, steps on said zone tapered toward the bobbin butt, a coating of enamel on said zone, a layer of electric conducting paint on the enamel on said zone, and a metallic ferrule bonded to said layer of paint.

4. The method of making a bobbin for use with the electric detecting system of a loom, the method consisting in the following steps: forming a bobbin body with a detecting zone tapering generally from the butt toward the tip of the bobbin and

25 forming steps on the detecting zone, providing the bobbin with a waterproofing coating, placing a layer of electric conducting paint on the coating 30 on the detecting zone, and electrolytically depositing a metal ferrule on the layer of paint.

5. The method of making a bobbin for use with the electric detecting system of a loom, the method consisting in the following steps: forming a bobbin body with a detecting zone tapering generally from the butt toward the tip of the bobbin and forming steps on the detecting zone, at least one of said steps being of such form that one diameter thereof is less than another diameter thereof more distant than said one diameter from the butt, providing the detecting zone with a coating of waterproofing material, placing a layer of fluid electric conducting material on the coating on the detecting zone, and electrolytically 45 depositing a metallic ferrule on said layer of conducting material.

6. The method of making a bobbin for use with the electric detecting system of a loom, the method consisting in the following steps: forming a bobbin body with a detecting zone tapering generally from the butt toward the tip of the bobbin and forming steps on the detecting zone which taper toward the butt, providing the bobbin with a waterproofing coating, placing a layer of electric conducting paint on the coating on the detecting zone, and electrolytically depositing a metal ferrule on the layer of paint.
